UNITED STATES PATENT OFFICE.

EVERARD N. WHETSEL AND MORTON C. BRADLEY, OF BLOOMINGTON,
INDIANA.

COLLAR-BUTTON AND NECKTIE-HOLDER.

SPECIFICATION forming part of Letters Patent No. 663,203, dated December 4, 1900.

Application filed February 7, 1900. Serial No. 4,350. (No model.)

To all whom it may concern:

Be it known that we, EVERARD N. WHETSEL and MORTON C. BRADLEY, citizens of the United States, residing at Bloomington, in the county of Monroe and State of Indiana, have invented a new and useful Collar-Button and Necktie-Holder, of which the following is a specification.

Our invention relates to collar-buttons, and 10 has for its object to provide what is known as a "folding button," with means for retaining the tie or cravat in position after the button has been inserted through the collar; and it 15 consists in the improved construction and novel combination of parts of the same, as will be hereinafter more fully set forth.

In the accompanying drawings, in which the same reference-numerals indicate corresponding parts in each of the views in which 20 they occur, Figure 1 is a perspective view of our improved collar-button in position. Fig. 2 is a sectional view of the same, some of the parts being shown in two positions. Fig. 3 is a top plan view of the top of the button, and Fig. 4 is a detail view.

Referring more particularly to the drawings, 1 indicates the base and stem of our improved collar-button, which may be of any ordinary construction, to the top of which is 30 pivotally secured in the usual manner the top portion 2. The top 2 is provided with a suitable opening 3, preferably substantially heart-shaped, at the base of which the top is provided with a projection 3', and the point 35 is provided with a groove 4.

Rigidly secured to the stem in any usual manner—as, for instance, by means of rivets 5—is a pin 6, the free end of which is pointed and projects through the opening in the top 40 when the top is turned transversely of the stem in position for use. Adjacent to the point the pin is provided with an opening 7, into which the projection 3' extends when the top is in its transverse position and locks the 45 top against being accidentally moved out of that position. The point of the pin, which is preferably slightly curved toward the point of the top of the button, fits within the groove 4 at the point of the opening in the top of the 50 button when the top is extended parallel with the stem ready for insertion in the garment.

In using our improved collar-button the top is swung upon its stem in the usual manner, which will thereby house the point of the pin and permit of the ready insertion of 55 the top through the buttonhole. As soon as the button has been inserted the top is swung down into a position at right angles to the stem of the button in the usual manner; but as the point of the pin normally extends 60 above the pivotal point of the top it is evident that as soon as the top is swung down into its position the point of the pin will be caused to protrude or extend beyond the top of the button in position to engage with the 65 tie or cravat and prevent the same from sliding up toward the top of the collar. By curving the point of the pin toward the point of the top of the button the pin will project slightly downward when in position for better 70 engagement with the tie or cravat, and thereby avoid the necessity of causing the pin to project to such an extent through the top. As soon as the top reaches the limit of its transverse movement the projection at the base 75 of the opening in the top enters the opening in the pin, and thereby locks the parts against movement relatively to each other until after the point of the pin has been withdrawn sufficiently to disengage it from the 80 projection in the top.

The pin is preferably made from a flat piece of spring material of a less width than the stem of the button, so that when it is secured thereto the button can be inserted in 85 the garment in the usual manner, and the presence of the pin will scarcely be noticed.

While we have intended the button for use at the front of a collar for engaging with the tie direct, it could be used at the back and 90 the point of the pin be made to engage with the string portion of the tie and prevent its moving toward the top of the collar. We also reserve to ourselves the right to make 95 such changes or alterations in the form and construction of the different parts of our button as will come within the scope of our invention.

Having thus fully described our invention, what we claim as new, and desire to secure by 100 Letters Patent of the United States, is—

The combination, with a collar-button, the

top of which is pivotally secured to the stem and is provided with a substantially heart-shaped opening, said top being grooved at the point of the opening and provided with 5 a projection at its base, of a pin secured to the stem and having its free end pointed and perforated and projecting through said opening and in engagement with the projection

thereof when the top is folded, and housed within the groove when the top is extended, substantially as described.

EVERARD N. WHETSEL.
MORTON C. BRADLEY.
